CLAIM

The ornamental design for an ECG lead wire connector, as shown and described.

DESCRIPTION

FIG. 1 is a perspective view of the front, top, and left sides of an embodiment of an ECG lead wire connector;

FIG. 2 is a perspective view of the front, bottom and right sides of the ECG lead wire connector illustrated in FIG. 1; FIG. 3 is a plan view of the top of the ECG lead wire connector illustrated in FIG. 1;

FIG. 4 is a plan view of the bottom of the ECG lead wire connector illustrated in FIG. 1;

FIG. 5 is an elevation view of the front of the ECG lead wire connector illustrated in FIG. 1;

FIG. 6 is an elevation view of the rear of the ECG lead wire connector illustrated in FIG. 1;

FIG. 7 is an elevation view of the right side of the ECG lead wire connector illustrated in FIG. 1; and,

FIG. 8 is an elevation view of the left side of the ECG lead wire connector illustrated in FIG. 1.

The broken line portion of the figure drawings is included to show portions of the article that form no part of the claimed design.

1 Claim, 3 Drawing Sheets
